UNITED STATES PATENT OFFICE

2,506,590

HIGH-FREQUENCY TUBE STRUCTURE

William W. Hansen, Garden City, N. Y., assignor
to The Sperry Corporation, a corporation of
Delaware

Application October 31, 1941, Serial No. 417,229

22 Claims. (Cl. 315—6)

1

This invention relates, generally, to high frequency tube structures having attached resonant members and of the type shown in Patent No. 2,242,275, issued May 20, 1941, in the name of Russell H. Varian, and more specifically, to a high frequency tube structure of the above type having very large power output.

Stated somewhat fully, the principal object of the invention is the provision of an improved and practicable embodiment of high frequency tube structure utilizing principles disclosed in the above-identified patent, the device in the present invention employing two hollow resonators with an electron beam projecting through them, the second of said resonators being arranged in sections such that a unidirectional voltage may be applied between the sections of said resonator.

More broadly, an object of the invention is to provide high frequency tube structures, useful as high power power-amplifiers, oscillators, modulators, multipliers, detectors, etc.

Another object of the invention is to provide an improved resonator structure suitable for use in the aforementioned type of tube structures and having a construction such that unidirectional or modulating voltages may be applied between the grids or active portions of said resonator.

A further object of the present invention is to provide an improved electron tube device formed substantially as a figure of revolution.

Another object of the present invention is to provide a low pass filter construction suitable for use with such a resonator, and having characteristics such that unidirectional voltages may be applied through the filter to the resonator grids or active portions and such that ultra high frequency current does not leak out of the resonator at the point of application of the unidirectional voltage.

A further object of the invention is to design a portion of such a resonator so that said portion acts as the first element of such a filter.

A still further object of the invention is the provision of an ultra high frequency tube structure suitable for use as a power amplifier, an oscillator, or for other uses, having annular resonators, grids, and an annular filter structure, and capable of a very high power output.

Still another object of the invention is to provide a low pass filter suitable for filtering out ultra high frequencies and passing only unidirectional voltages such as are useful for beam voltages, heater voltages, control voltages, or buncher resonator acceleration voltages, or for passing very low frequency modulation voltages.

2

such as are used in the aforementioned ultra high frequency tube structures.

Other objects and advantages will become apparent from the specification, taken in connection with the accompanying drawings wherein the invention is embodied in concrete form.

In the drawings,

Fig. 1 is a fragmentary cross-section view of a preferred form of the invention.

10 Fig. 2 is a longitudinal cross-section view of a low pass filter structure, useful in explanation of the operation of a portion of the structure shown in Fig. 1.

Fig. 3 is an equivalent circuit of the filter of Fig. 2.

15 Fig. 4 is an explanatory diagram useful in explaining the operation of the invention.

Fig. 5 is a further explanatory diagram.

Fig. 6 is a cross-section view of a modification 20 of the invention useful as a high power amplifier or oscillator at ultra high frequencies.

Similar characters of reference are used in all of the above figures to indicate corresponding parts.

25 Fig. 1 shows in cross-section one form of the invention. Hollow resonant cavities 1 and 2 are shown carried by the adjacent inner ends of conducting tubular members 3 and 4, the inner ends of tubular members 3 and 4 being closed by flexible corrugated disc walls 5 and 6. Walls 5 and 6 have centrally located openings through which drift tube 7 projects. The other flat wall of resonator 2 is formed by disc 8, said disc having a centrally located aperture enclosing a grid structure 9. Drift tube 7 projects through flexible wall 6 to act as a mount for grid structure 10 positioned opposite and adjacent to grid 9. The form and operation of grid structures 9 and 10 and of resonator 2 has been disclosed in Fig. 7

30 of copending application Serial No. 343,528, filed July 2, 1940, in the names of William W. Hansen, Sigurd F. Varian, and Russell H. Varian, now Patent No. 2,311,658, granted February 23, 1943, and in prior disclosures. These grids may be 35 omitted if desired. Resonator 2 is supplied with the two coaxial line leads 11 and 12, which are terminated in the resonator 2 by coupling loops 13 and 14, respectively. Attached concentrically to tubular wall 4 as by means of a flange 15 is

40 a tubular member 16, which may be of a metal suitable for sealing to a glass portion of the envelope (not shown) which acts as a support for cathode structure 17, as is shown in the aforementioned Patent No. 2,311,658 and in other disclosures. 45 Resonator 2 is supplied with the two coaxial line leads 11 and 12, which are terminated in the resonator 2 by coupling loops 13 and 14, respectively. Attached concentrically to tubular wall 4 as by means of a flange 15 is a tubular member 16, which may be of a metal suitable for sealing to a glass portion of the envelope (not shown) which acts as a support for cathode structure 17, as is shown in the aforementioned Patent No. 2,311,658 and in other disclosures. 50 On drift tube 7 is mounted disc-shaped

flanged member 18, which may serve as a support for the tube.

Resonator 1, which has some of the chief features of the present invention, is attached to drift tube 7 oppositely to resonator 2 by means of flexible corrugated wall 5 in a manner such that drift tube 7 projects inwardly into resonator 1, the resonator end of the drift tube 7 carrying grid structure 19. Wall 21, which is electrically insulated from tubular member 3, supports grid 20 in a cavity 22 opposite and adjacent to grid 19, grid 20 and cavity 22 thereby acting to suppress secondary electrons or to prevent them from returning into resonator 1 and drift tube 7. Wall 21 is mounted as an end plate in tubular member 23, which extends inwardly and coaxially into resonator 1. The clearance space 24 between concentric tubular members 3 and 23 is adjusted in width to obtain proper capacitive coupling between members 3 and 23, thus affording a closed path for the high frequency alternating currents which flow on the inner walls of resonator 1 to and from grids 19 and 20, while further providing insulation for any unidirectional or low frequency voltages which may be applied between grids 19 and 20. The space 24 may be occupied by a dielectric material 24', and may be made to have an extremely low impedance by means of a filter structure yet to be described.

Mounted in tubular wall 3 are oppositely positioned coaxial line members 25 and 26, which project through apertures 27 and 28 in tubular wall 23, respectively, and which terminate inside resonator 1 in inductive coupling loops 29 and 30, respectively.

In order to describe the concentric line filter system used with resonator 1 to prevent leakage of energy from resonator 1 through space 24, Figs. 2 and 3 are shown, illustrating a concentric line filter operating on the same principle as that used with resonator 1, as will be described below. As seen in Fig. 2, the outer tubular conducting member 31 of the filter encloses concentrically a thin tubular dielectric member 37 which fits closely into the inner diameter of tube 31. Concentric with both tubes is a conductor 32, which, at approximately quarter wave length intervals, expands into approximately quarter wave length long conducting members 35 which are substantially equal in diameter to the inner diameter of dielectric tube 37. The illustrated filter contains distributed inductance and capacity along its length. Sections 34 are effectively inductive while sections 35 are effectively capacitive, as diagrammatically illustrated in the approximately equivalent circuit of Fig. 2. The relative distributed capacity and inductance values are determined by the proportions selected for the relative dimensions of inner and outer conductor. Elements 35, which act effectively as capacitances, and spaces 34, which act effectively as inductances, are preferably made electrically one quarter wave length long, this wave length being measured in the dielectric material of tube 37. The unit is held rigidly together by means of insulators 33 which fit into opposite ends of tube 31 and are held in it by means of screws 39. The unit then performs as a series inductance multi-T-section uniform-section filter. Dielectric tubular member 37 may be omitted if desired, the relative diameters of capacitive elements 35 and of outer conducting tubular members 31 being left approximately as shown.

Such a filter may be used to introduce volt-

ages such as heater voltages, cathode voltages, modulation voltages, etc., through a wall of a shielding box surrounding a high frequency tube, or other high frequency apparatus, thereby preventing any high frequency radiation from leaking out of the box to disturb other high frequency circuits in the vicinity of the shielded tube, or for other related purposes. In Fig. 2 we have shown the filter projecting through conducting wall 38 of such a shielding box. Screws 39 and the ends of conductor 32 serve as terminals for the filter.

Normally very few sections are needed in such a filter to give substantially complete attenuation of the frequency that is desired to be suppressed. The filter circuit behind resonator 1 of Fig. 1 is shown with only two such sections, although a larger number may be used. Here the outer tubular conducting wall 3 of resonator 1 is continued to enclose the filter structure and acts as did tube 31 of Fig. 2. The chambers 40 of the filter are made somewhat broadly resonant to the frequency at which resonator 1 operates, said chambers 40 being about one quarter wave length long. The inner conductor of the concentric line is made small in diameter as at 41, and expands in diameter to nearly equal the inner diameter of tubular member 3 to form capacitative element 42, whose length is substantially a quarter wave length long. As previously mentioned, spaces 24 and 48 may be occupied by a ribbon or tube of dielectric such as that at 37 in Fig. 2 for supporting the inner filter elements and resonator member 23 and, thus removing some of the vibration load from glass to metal seal 46. In this event, capacitative element 42 will be electrically one quarter of a wave length long where wave length is measured in the dielectric. The inner conductor of the filter is then reduced in diameter at 47 to act as an inductive element, the chamber 40 being made resonant to the frequency to be suppressed. Tubular conductor 47 is extended through end wall 44 of end chamber 40, said tube 47 extending through glass end bell 46, and thus supporting the inner conductor 41 of the filter system and the inner portion 21, 23 of resonator 1, and providing a lead for the unidirectional or low frequency modulating voltage to be impressed across grids 19 and 20. Battery B is connected to provide a unidirectional voltage across grids 19 and 20, so that these grids are maintained at differing average or static potentials. As previously indicated, the above described filter arrangements provide for an extremely low impedance at the right end of space 24 in Fig. 1, looking from right to left in Fig. 1, thus increasing the ease of high frequency current flow across the gap between the resonator sections and resulting in substantial prevention of undesired leakage of high frequency energy from resonator 1.

In explanation of the above, and looking from right to left in Fig. 1, consider the unknown impedance of the concentric line at the left end of left quarter-wave space 40 to be Z_x . Let the characteristic impedances of the coaxial transmission lines formed by quarter-wave spaces 40 and 42 be Z_0 and Z_0' respectively. Thus Z_0' is therefore very much smaller than Z_0 under known concentric line theories. The line impedance at the left end of space 42 looking leftward is therefore quite high, being about

$$\frac{Z_0^2}{Z_x}$$

and the line impedance at the right end of space 42 looking leftward is very small about

$$\frac{Z_{02}^2}{Z_0^2} Z_x$$

Similarly the impedance at the left end of space 24 looking leftward is very high and the impedance at the right end of space 24 looking leftward is very low, progressively lower than that at the right end of space 42, especially where space 24 is of the indicated quarter-wave dimension.

The above explanation is in accord with known theories of quarter-wave transformer theory.

The filter elements 47, 42, and 41 are made hollow and partition 50 is provided so that cooling water, introduced, for instance, in portion 51 and removed in portion 52, may be used to cool the end wall 21 of resonator 1, especially providing cooling of the wall behind chamber 22 where the spent electrons give up their energy.

The flanged ring members 16' and 15, fastened to resonators 1 and 2, respectively, and flange 18, clamped around drift tube 7, may be used with tuning devices such as are disclosed in Patent No. 2,345,642, granted April 4, 1944 to Sigurd F. Varian and Russell H. Varian, and other disclosures therein mentioned.

To better understand the operation of the invention, the following theoretical analysis is given in connection with Figs. 4 and 5. Referring now to Fig. 4, there is shown diagrammatically elements of the structure shown in Fig. 1; namely, a cathode emitter surface 11', and grids 9', 10', and 19', 20', corresponding to grids 9, 10, and 19, 20 of resonators 1 and 2, respectively. Let V_0 be designated as the beam accelerating voltage, V_1 as the peak value of the high frequency voltage between the buncher grids 9' and 10', V_2 as the corresponding voltage between the catcher grids 19' and 20', and V as a unidirectional voltage also applied between grids 19' and 20'. Also, let I_0 be the beam current before the beam enters grid 9'; and I , the electron current before entering grid 19'. The instantaneous voltage across grids 9', 10' is then $V_1 \cos \omega t$ and across grids 19', 20' is $V + V_2 \cos \omega t$ where ω is 2π times the operating frequency. Considering Fig. 5, let it be assumed that no electrons are to be actually turned back between the catcher grids; this requires that V_2 be less than $V - V_0$. The resonator associated with the grids 19', 20' can then be considered as two resistances in parallel, R and R_L , where R is due to losses in the resonators (the resonator shunt resistance) and R_L is due to losses caused by loading, such as brought about in Fig. 1 by removal of energy from resonator 1 by means of coaxial line element 26. Let it be also assumed that the voltage V_1 is such as to give optimum bunching of the beam; i. e., it is assumed that I , the current entering grid 19', is made equal to $1.16 I_0 \cos \omega t$, as is explained by David L. Webster in the article "Cathode-ray bunching," Journal of Applied Physics, volume 10, July 1939. Reference may also be had in this connection to the article "Theory of klystron oscillators," David L. Webster, Journal of Applied Physics, volume 10, December 1939. Let it be further assumed that I_0 is constant and that R_L is adjusted to give V_2 such a value that electrons are just stopped between the grids 19', 20'. In that case:

$$V_2 = V_0 + V \quad (1)$$

$$V_2 = 1.16 I_0 \frac{R R_L}{R + R_L} \quad (2)$$

If power is removed from the catcher resonator associated with grids 19', 20', such power is, by definition of R_L :

$$P_{out} = \frac{V_2^2}{2R_L} \quad (3)$$

Combining (1) and (2) in (3):

$$P_{out} = .58 I_0 (V_0 + V) \frac{R}{R + R_L} \quad (4)$$

10 Then:

$$\text{Efficiency} = \frac{P_{out}}{P_{in}} = .58 \left(\frac{1}{1 + \frac{R_L}{R}} \right) \quad (5)$$

15 If it be assumed that $V=0$ and if R is very large compared to R_L , then

$$P_{out} = .58 I_0 V_0 \quad (6)$$

$$\text{Efficiency} = .58 \quad (7)$$

20 The Equations 6 and 7 are then applicable to a conventional high frequency tube of the type disclosed above and in prior disclosures, and may be derived from equations in the two aforementioned publications. Thus, increasing V in the 25 present invention gives larger P_{out} than for a conventional tube of the present type, the limit on P_{out} being set by the relation between V_0 and R_L as expressed by Equations 1 and 2. To find optimum V , Equation 4 is written as follows:

$$P_{out} = \frac{(1.16)^2}{2} I_0^2 R \frac{\frac{R_L}{R}}{\left(1 + \frac{R_L}{R}\right)^2} \quad (8)$$

35 This yields a maximum for $R_L=R$, or:

$$P_{out} = (.58 I_0) \left(\frac{1.16}{4} I_0 R \right) \quad (9)$$

Comparing Equations 6 and 9 it is noted that

$$\frac{1.16}{4} I_0 R$$

commonly greatly exceeds V_0 , so that the power output of the present invention for a given I_0 is greatly increased over that of the conventional tube of this type.

45 The arrangement provided by the present invention has practical advantages which render it superior to a conventional tube merely having the beam acceleration voltage raised to $V_0 + V$. As the electron beam traverses grids 9, 10 and 19, these grids intercept electrons which flow in a return circuit back to the positive side of the beam acceleration voltage source. The power loss represented by these return currents is obviously smaller where the acceleration voltage is V_0 than where it is $V_0 + V$. By introducing the additional acceleration voltage V at the catcher grids, the electron beam is subjected to 50 the same effective acceleration at the catcher as would be the case if the original acceleration voltage was equal to $V_0 + V$, and the power losses at the first three grids are held at a minimum.

55 Another practical advantage is that, where the beam acceleration voltage at the buncher is V_0 , the electrons traverse the drift space between grids 9 and 10 more slowly and hence may become bunched during a shorter drift space length than would be the case where the beam acceleration voltage at the buncher was $V_0 + V$. Thus, the invention enables the use of a shorter drift tube, providing a more compact tube.

Finally, since the power losses are low, it is 60 possible to obtain a higher power output for a

given beam current I_0 . By the same token it is possible to operate the device of the invention at a higher power level than a conventional tube with increased beam acceleration at the buncher.

The previous discussion may be qualitatively verified by regarding the source of I in Fig. 5 as a constant current (given I_0) generator in shunt with resistances R and R_L . Then maximum power output occurs when $R=R_L$. In a conventional tube of this type, the shunt resistance R is high, causing R_L to be also high, so that, with substantially constant current I (with constant I_0), V_2 would be large. This would cause V_2 to be larger than V_0 , thus reflecting electrons back into the buncher resonator from the region between grids 19' and 20'. The addition of V prevents this occurrence.

Although the tube structure shown in Fig. 1 is adaptable for use only as a power-amplifier or as an oscillator, theoretical considerations mentioned in the aforementioned applications and publications can be extended in describing modifications of the present invention adaptable as detector tubes, as multiplier tubes, etc. One may replace resonator 1 of Fig. 1 with one of smaller volume resonant to a harmonic of the buncher resonator 2, as disclosed in United States Letters Patent No. 2,280,824, issued April 28, 1942, and in the aforementioned publications. For use as a multiplier tube, the dimensions of resonator 1 and its attached filter structure will be determined again by the output wavelength.

The modification of the present invention shown in Fig. 6 is particularly useful as an ultra-high frequency power amplifier or as an oscillator. Fig. 6 illustrates a figure of revolution as generated by rotation of the cross-section of Fig. 1 about an axis eccentric thereto, slightly modified to show use of a focusing annular cathode structure 53 and gridless annular resonators 54 and 55. From cathode 53 a tubular, electron beam slightly focused by annular member 90 passes through annular buncher resonator 54 and is thereby velocity grouped or bunched in traversing annular drift tube 56, so that it releases part of its energy in annular resonator 55, being stopped by wall 57. Resonator 55 is again made up of annular concentric portions. One portion consists of inner supporting cylindrical conducting member 58, apertured flexible diaphragms 62 and 63, and external conducting tubular member 64. The other portion of resonator 55 consists of apertured wall 57 and tubular members 65 and 66, located concentric to support 58. Tubular member 65 affords capacitive coupling to support member 58; while tube 66 serves to likewise capacitively link the wall 57 to external tube 64, thus again providing a closed path for the high frequency currents flowing on the inner surfaces of resonator 55, meanwhile allowing a unidirectional voltage or a low frequency modulating voltage or both to be applied to the immediate boundaries of the annular gridless orifices 67, 68. Thus, it will be noted that either of the parts of the resonator 55, associated with orifices 67 or 68, constitute an electrode.

Annular filter sections 69, 70 function similarly to the filter described in Fig. 1. Filter element 70 has a hollow annular internal cavity 91, which may be supplied with cooling water through tubes 71 and 72, which extend through end wall 73 and are supported by two glass bell-jar members 74 and 74' placed on a diameter of wall 73. Heat may also be removed from the

cylindrical chamber 60 between flexible diaphragms 62 and 63 by allowing a cooling fluid to flow through axial bore 61 in support 58 and out through bore 59. A further purpose of bores 59 and 61 is to relieve pressures in chamber 60 caused by differential deformation of the flexible diaphragms 62, 63, and 62, 83 in tuning resonators 55 and 54, respectively. Coaxial line coupling elements 75 and 76 are provided in resonator 54, and coaxial line coupling elements 77 and 78 are mounted in resonator 55 in the manner shown in Fig. 1. Flanges 79, 80 and 81 are provided for any conventional resonator tuning devices as described in the aforementioned applications and in others therein referred to. The pipes 71 and 72 serve to support the inner portion of annular resonator 55 and its associated annular filter element, supply cooling means to said resonator portion, and provide means for impressing the voltage V across the two sections 67, 68 of resonator 55.

From the above description of Figs. 1 and 6 it is evident to one skilled in the art that a similar resonator and filter unit construction may be applied to the buncher resonator of any high frequency tube of the present type, thus providing the possibility of introducing a unidirectional voltage or a low frequency modulation voltage to the grids of the buncher resonator. It is also evident to one skilled in the art, that a high power output structure may be obtained in a manner similar to that in which the structure of Fig. 6 was conceived by placing the axis about which the cross-section of Fig. 1 is rotated perpendicular to the axis of Fig. 1, instead of parallel to the axis of Fig. 1 as was done in obtaining the structure of Fig. 6.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

45 What is claimed is:

1. High frequency apparatus comprising means including a cathode for projecting an electron stream along a predetermined path, a pair of cavity resonators spaced from said cathode and each having a pair of axially aligned apertures along said path and similar grid structures mounted respectively in each of said apertures, whereby the resonator closer to said cathode is adapted to velocity modulate the electrons passing through its pair of grid structures and the resonator farther from said cathode is adapted to extract energy from the electrons passing through its pair of grid structures, and potential source means coupled to the grids of one of said resonators for maintaining said latter grids at different average potentials, whereby for a given beam current greater power output may be obtained from said apparatus.

65 2. High frequency apparatus comprising means including a cathode for producing a stream of electrons flowing along a predetermined path, a first cavity resonator spaced from said cathode and surrounding said path and coupled to said stream to velocity modulate the electrons thereof, a drift tube defining a field-free space surrounding said path beyond said resonator, a second cavity resonator surrounding the path of said stream beyond said drift tube and coupled to said stream to extract high frequency energy

therefrom, said second resonator comprising two relatively insulated sections and potential source means coupled to said sections for maintaining said sections at different average potentials.

3. Apparatus as claim 2 wherein each of said sections is constituted in part of an apertured wall, said walls being insulated and in the path of said stream, said potential means including a source of unidirectional potential, and means connecting said source between said walls with the positive terminal connected to the wall farthest from said first cavity resonator, whereby increased power output may be obtained from said apparatus at higher efficiency.

4. High frequency electron velocity modulation apparatus comprising a pair of spaced aligned hollow resonators each having a pair of electron-permeable wall regions, means defining a field-free drift space between said resonators, and means in said apparatus including a cathode outside said resonators for producing an electron stream and for projecting said stream successively through the regions of one of said resonators, said drift space and the regions of the other resonators, whereby said electron stream may be velocity modulated during its traverse of the gap between the electron-permeable wall regions of said one resonator and said other resonator is adapted to extract energy from said stream during its traverse of the gap between the wall regions of said other resonator, at least one of said resonators being composed of two insulated capacitively coupled conductive sections.

5. Apparatus as in claim 4, further including a source of unidirectional potential and means connecting said source between said sections whereby increased power output at higher efficiency may be obtained from said apparatus.

6. High frequency electron discharge apparatus comprising means including a cathode for projecting an electron stream along a predetermined path, means spaced along said path from said cathode for velocity-modulating the electrons of said stream, means defining a field-free drift space surrounding said path beyond said modulating means, a cavity resonator beyond said drift space having an electron-permeable wall region in the path of said stream, whereby said stream is directed into said resonator and said resonator is adapted to extract energy from said stream, said resonator comprising a pair of insulated conductive sections, and means coupled to said sections for impressing a direct voltage therebetween for maintaining said sections at different average potentials whereby increased power output and higher efficiency may be obtained from said apparatus.

7. Ultra high frequency apparatus comprising means including a cathode for projecting an electron stream along a predetermined path, means along said path spaced from said cathode for velocity-modulating the electrons of said stream by a high frequency signal, means defining a field-free drift space surrounding said path beyond said modulating means, whereby said velocity-modulated electrons may become density modulated by velocity grouping action, and means in the path of said density modulated electrons for extracting high frequency energy therefrom, said last-named means comprising a pair of relatively insulated electron-permeable members in the path of said stream, means coupled to said members and defining a hollow cavity resonator, a source of electron-ac-

celerating voltage, and means connecting said source between said members, whereby increased power may be extracted from said stream at higher efficiency.

5 8. Ultra high frequency apparatus comprising means defining a hollow resonator including two concentric closely spaced insulated members, the inner of said members being substantially a quarter-wave length long at the operating frequency thereof to provide a quarter-wave transmission line section of low characteristic impedance with the outer of said members, and filter means within said apparatus blocking leakage of high frequency energy outwardly from said resonator through the gap between said members, said filter means comprising a concentric transmission line having inner and outer conductors connected respectively to said respective resonator members, said transmission line having a section of a length substantially equal to a quarter-wave length, and of a characteristic impedance substantially larger than the characteristic impedance of said first-named quarter-wave length section, whereby a very low impedance is obtained at the gap between said two members.

9. High frequency apparatus comprising a cylindrical outer member, a second member concentrically mounted within said outer member and projecting therewithin and connected to one end of said outer member, a third wall member within said outer member opposite the inner end of said second member and insulated from said outer and second members, said three members defining a hollow cavity resonator, and means preventing leakage of high frequency energy from said resonator by way of the gap between said outer member and said wall member, said last-named means comprising conductive means within said outer member forming a coaxial transmission line therewith and having successive portions of length substantially equal to a quarter-wavelength at the operating frequency of said resonator and of alternately relatively large and small characteristic impedance whereby the impedance at said gap is transformed to a low value to prevent said energy leakage.

10. High frequency apparatus comprising a cylindrical outer member, conductive means defining a resonator wall connected at one end of said outer member, further conductive means defining another wall of said resonator insulated from said outer member and mounted therewithin, said outer member, conductive means and further conductive means defining a cavity resonator, and means preventing leakage of high frequency energy out of said resonator by way of the gap between said outer member and said insulated member, said last-named means comprising conductive means within said outer member forming a coaxial transmission line therewith and having successive portions of length substantially equal to a quarter-wavelength at the operating frequency of said resonator, the first of said portions having relatively large diameter forming a concentric transmission line of relatively small characteristic impedance with said outer member and the second of said portions having relatively small diameter to form a relatively larger characteristic impedance with said outer member, whereby the impedance at said gap is transformed to a low value to prevent said energy leakage.

11. High frequency apparatus comprising a tubular conductive member, conductive means de-

fining a resonator wall connected at one end of said tubular member, further conductive means defining another wall of said resonator and insulated from said tubular member, said tubular member and two conductive means defining a cavity resonator, and means preventing leakage of high frequency energy out of said resonator by way of the gap between said tubular member and said insulated wall-defining means, said leakage-preventing means comprising a concentric transmission line having inner and outer conductors connected to said tubular member and said wall-defining means, said line having a section of relatively low characteristic impedance and of a length of substantially one-quarter wave-length at the operating frequency of said resonator and adjacent said resonator, and also having a second section connected to said first section and of relatively high characteristic impedance compared to that of said first section and of a length of substantially one-quarter wave-length.

12. High frequency apparatus comprising means defining a hollow resonator including a pair of closely spaced concentric tubular members having a tubular dielectric member therebetween, an end wall connected to one of said members, a flexible wall connected to the other of said members, and a reentrant hollow tubular member mounted on said flexible wall concentrically with respect to said tubular members and having a flat end face substantially parallel to said first end wall and adjacent thereto.

13. Apparatus as in claim 12, further including means for projecting an electron stream axially through said tubular reentrant wall and end face into said resonator, and means coupled to said first two tubular members for maintaining said latter members at different average potentials.

14. High frequency apparatus for use in an electron-discharge device comprising means defining a hollow resonator comprising two closely spaced concentric substantially cylindrical conductive sections providing a capacitive coupling therebetween, one of said sections carrying a concentric conductive member reentrant therewithin as a conductive continuation of said one section and with an electron-permeable region on the inner end of said reentrant member through which an electron beam may be axially projected from externally of said resonator and means coupled to said sections for maintaining said sections at different average potentials.

15. Apparatus as in claim 14, wherein said reentrant portion is axially adjustable with respect to said sections, whereby tuning of said resonator may be effected.

16. A high frequency electron discharge device comprising a cylindrical outer member having a concentric axially reentrant portion, said reentrant portion having a concentric opening therein, a second cylindrical member positioned concentrically within said first member and insulated therefrom, and forming a hollow resonator with said first member by capacitive coupling therewith, one of said members having an electron permeable region through which an electron beam may be projected, and filter means also positioned within said first member for preventing high frequency energy leakage from said resonator through the insulation between said first and second members.

17. A device as in claim 16, in which said filter

device comprises a plurality of sections of conductor forming quarter-wave transmission line sections with said outer member, said sections being spaced by quarter-wave capacitive loading sections.

18. A high frequency electron velocity modulation device comprising means defining a hollow resonator having two generally annular, capacitatively coupled, concentric, conductive members, one of said members having a substantially annular electron-permeable region through which an electron beam may be projected from the exterior of said resonator, and means coupled to said members for maintaining said members at differing average potentials, filter means within said device for blocking leakage of high frequency energy from said resonator, said filter means comprising a concentric conductor transmission line having inner and outer conductors connected to the respective resonator members, with said resonator members forming a quarter-wave capacitive loading section in said line.

19. High frequency apparatus comprising means including a cathode for producing an electron stream, a pair of cavity resonators mounted along the path of said stream spaced from said cathode and separated by a field-free drift space surrounding said stream path, each of said resonators having a pair of electron-permeable wall portions serving as electrodes in the path of said stream, whereby the pair of said electrodes closer to said cathode is adapted to velocity modulate said electron stream and the other pair of said electrodes is adapted to extract energy from said stream, one of said resonators having two relatively insulated sections, and a source of modulating voltage connected between said sections.

20. High frequency apparatus as in claim 19, further including means coupling said resonators together, whereby self-sustained oscillations modulated by said voltage are produced.

21. An electron discharge device comprising an outer cylinder having a fixed end wall at one end thereof and a flexible end wall at the other end thereof and having a tubular passage coaxial with the cylinder through both end walls and spaced both from the axis and from the cylindrical wall, an annular cathode opposite one end of said tubular passage, and an annular electrode at the other end of said passage.

22. An electron discharge device comprising an outer cylinder having a fixed end wall at one end thereof and a flexible end wall at the other end thereof and having a tubular passage coaxial with the cylinder through both end walls and spaced both from the axis and from the cylindrical wall, and an annular cathode opposite one end of said tubular passage.

WILLIAM W. HANSEN.
